Primary Examiner — Kevin Rudzinski*Assistant Examiner* — John Reickel*(74) Attorney, Agent, or Firm* — Baker Botts L.L.P.(57) **CLAIM**

The ornamental design for a display screen or portion thereof with a graphical user interface of a mobile device, as shown and described.

DESCRIPTION

FIG. 1 is a front view of a first embodiment of a display screen with a graphical user interface of a mobile device; and, FIG. 2 is a front view of a second embodiment of a display screen with a graphical user interface of a mobile device. The broken line showing a display screen and user interface elements is for the purpose of illustrating portions of the article and forms no part of the claim.
